UNITED STATES PATENT OFFICE.

FRED HABENSACK, OF SAG HARBOR, NEW YORK, ASSIGNOR TO THE ALVIN MANUFACTURING COMPANY, OF NEW YORK, N. Y.

DESIGN FOR A BACK FOR BRUSHES OR SIMILAR ARTICLES.

SPECIFICATION forming part of Design No. 29,464, dated October 11, 1898.

Application filed August 30, 1898. Serial No. 689,871. Term of patent 3½ years.

To all whom it may concern:

Be it known that I, FRED HABENSACK, a subject of the Emperor of Germany, residing at Sag Harbor, in the county of Suffolk and 5 State of New York, have invented and produced a new and original Design for the Backs of Brushes or Similar Articles, of which the following is a specification, reference being had to the accompanying drawing, which shows the back of a brush or similar article having my design applied thereto.

The leading or characteristic feature of my design consists of two raised ribs running parallel with the greater portion of the outer 5 edge of the back and handle of the article, said ribs being intersected in their length with a number of leaf-like figures, the outer ribs being beaded. The said several ribs terminate at their upper and lower ends in o fanciful scrolls, a bouquet of flowers being located between the upper scroll and extreme end of the back, and also between the lower scroll and extreme outer end of the handle.

Referring to the drawing, A represents the back of a brush or similar article, the central 25 field of which is left plain, and B the handle. Near the outer edge of the back and handle and parallel therewith extend the raised ribs C D, the outer rib C being beaded, as shown. These ribs are intersected at a number of 30 points in their length by the leaf-like figures E and terminate at their upper ends in the scrolls F and at their lower ends in the scrolls G. Between the scrolls F and the outer end of the back is located a bouquet of flowers H, 35 and between the scrolls G and the outer end of the handle is located the bouquet of flowers I, all as shown.

What I claim is—

The design for the back of a brush or similar article, substantially as shown and described. 40

FRED HABENSACK.
